UNITED STATES PATENT OFFICE

FRANKLIN G. SLAGEL, OF BUFFALO, NEW YORK, ASSIGNOR TO FEEDERS MANUFACTURING COMPANY, INC., OF BUFFALO, NEW YORK, A CORPORATION OF NEW YORK

VAPORIZER FOR REFRIGERATOR SYSTEMS

Application filed April 1, 1929. Serial No. 351,482.

This invention relates to a vaporizer for mechanical refrigerating systems which are more particularly intended for commercial purposes such as display cases or storage compartments of grocers, meat markets, restaurants, and the like where larger quantities of foodstuffs and similar goods must be preserved or kept in condition than is usually required in a domestic refrigerator.

10 The objects of this invention are the provision of a vaporizer for this purpose which can be used either in a wet or a dry refrigerating system which can be built up in sections of different numbers and therefore 15 possesses the requisite flexibility to meet different requirements, and which is so organized that the number of soldered joints is considerably reduced, less radiating plates or fins are employed, less metal is required 20 for a given cooling capacity, and the formation of ice on the vaporizer is reduced to a minimum, and thereby maintains the refrigerator system in the highest state of efficiency.

25 In the accompanying drawings:

Fig. 1 is a vertical longitudinal section of a vaporizer embodying a form of my invention.

Fig. 2 is a bottom plan view of the same.

30 Fig. 3 is a rear end view of the vaporizer.

Figs. 4 and 5 are vertical transverse sections taken on the correspondingly numbered lines in Fig. 1.

Fig. 6 is a vertical longitudinal section 35 of a vaporizer for use in a wet system and employing a single set of vaporizing tubes.

Fig. 7 is a top plan view of the same but showing the brine tank in section.

Fig. 8 is a rear end view of the vaporizer 40 shown in Fig. 7.

Fig. 9 is a vertical transverse section taken on line 9—9, Fig. 7.

Fig. 10 is a fragmentary cross section taken on line 10—10, Fig. 1.

45 In the following description similar characters of reference indicate like parts in the several figures of the drawings.

Referring to Figs. 1—5, the numeral 10 represents a vaporizing chamber or tank into 50 which the refrigerant such as ethyl chloride

is introduced in liquid form through an inlet 11 in the lower part of the front head 12 of this chamber and discharged in vaporized form through an outlet 13 in the upper part of this head. The admission of liquid refrigerant into this chamber is automatically controlled by a float valve mechanism which is responsive to variations in the level of the liquid refrigerant in this chamber, this valve mechanism may be variously constructed and 55 may consist of a needle valve 14 controlling said inlet, a float 15 rising and falling with the liquid level in the chamber, and an elbow lever 16 pivoted on the front head of the chamber and having one arm engaging the 60 needle valve 14 and another arm connected with said float.

In the form of the vaporizer shown in Figs. 1—5 the same includes two sets of parallel vaporizing tubes which are arranged one 70 above the other. The tubes of the upper set comprise two upper horizontal tubes 17 of comparatively large diameter and three lower horizontal tubes 18 of comparatively small diameter, the several tubes being arranged 75 to practically form an annular row, as shown in Figs. 4 and 5. The front ends of the tubes of the upper set are secured in openings in the rear head 19 of the vaporizing chamber by soldering or otherwise so that 80 these tubes communicate with this chamber.

The rear ends of the tubes of the upper set are connected by a manifold which preferably has the form of a hollow ring into different parts of which these tubes open and 85 are placed in communication with each other. In the preferred construction of this manifold ring the same consists of an annular channel shaped rear section 20 which is drawn out of a single sheet of metal and 90 a flat annular front section 21 stamped out of sheet metal and connected at its inner and outer edges by seams 22, 23 with the corresponding edges of the rear channel section. The front ring section is provided with a 95 plurality of openings in which the rear ends of the tubes of the upper set are secured by soldering or any other suitable means to produce a tight joint therewith. For the purpose of increasing the area of contact 100

between the tubes and said front manifold section the openings in the latter are provided with collars 24 surrounding the tubes, as shown in Fig. 1.

5 This form of manifold is much lighter and contains less metal, is easier to make and therefore less expensive than the manifolds heretofore known.

The refrigerating liquid enters the lower 10 vaporizing tubes of the upper set as well as the lower part of the hollow ring shaped header or manifold and the vapors resulting from heating of the liquid by the surrounding heat pass into the upper part of this 15 manifold and thence through the upper vaporizing tubes and into the upper part of the vaporizing chamber.

In order to increase the heat absorbing capacity of the vaporizing tubes of the upper set a plurality of heat absorbing fins are provided each of which preferably consists of a sheet metal plate 25 which is bent to form a plurality of corrugations 26 so as to increase the heat absorbing capacity of the 25 same and each of these plates being provided with a plurality of openings which receives the tubes of the upper set. Each of these openings is preferably surrounded by a collar 27 on the respective plate which 30 is secured to the tube within the same by solder or otherwise, thereby producing joints of large area between the tubes and the fins whereby the heat absorbed by the fins is more effectively transmitted to the tubes and 35 to the refrigerant within the same.

The absorber plates are mounted on the tubes of the upper set and spaced a sufficient distance apart from one another so that any ice forming thereon will not be able to 40 bridge and completely fill the space between adjacent fins, thereby constantly presenting a comparatively large area to the compartment which is to be cooled and providing the maximum cooling efficiency.

45 Stiffening of these absorber fins so that they are not liable to be easily bent out of shape is preferably accomplished by forming beads or ribs 28 across the angles or corners of the corrugations on these fins, as shown in Figs. 1 and 2.

For refrigerators of comparatively small capacity the upper set of vaporizing tubes connected with the vaporizing chamber and head or manifold and provided with the 55 absorbing fins will answer requirements, but for refrigerators of larger capacity one or more additional heat absorbing units may be added in accordance with the needs of the particular installation and connected 60 with the vaporizing chamber.

When adding but one further unit the same may be arranged below the main or initial unit previously described which added unit, in the construction shown in Fig. 65 1, is arranged below the initial unit and com-

prises a plurality of elbow shaped vaporizing tubes having parallel main parts 29 arranged below the tubes of the initial unit and upwardly turned parts 30 arranged at the front ends of the main parts 29 and secured in openings in the underside of the vaporizing chamber, as shown in Fig. 1.

The rear ends of the tubes of the auxiliary unit are connected with a hollow ring shaped header manifold which is constructed in all respects like the corresponding header or manifold of the initial or main header or manifold, and the same, as shown in Figs. 1, 2 and 3, comprises a rear annular channel shaped section 31, a front annular flat section 32 secured at its inner and outer edges with the corresponding edges of the channel section by inner and outer seams 33, 34, and collars 35 formed on the front manifold section around the openings which receive the respective tubes and secured to the latter by solder to form a tight joint.

The set of tubes of the lower unit are filled with liquid refrigerant due to the connection of these tubes at their front ends with the underside of the vaporizing chamber, but a longitudinal circulation of the refrigerant medium through these tubes and those of the initial unit is made possible by the provision of transfer pipes 36 of U-shape which have their upper ends secured in openings in the lower part of the flat front side of the upper header or manifold while the lower ends of these transfer pipes are secured in openings in the upper part of the flat front side of the header or manifold of the lower absorber unit, as best shown in Figs. 1 and 3.

By these means a rapid circulation of the refrigerant is possible and the cooling capacity of the vaporizer is increased accordingly. The lower absorber unit may have the horizontal parts of its tubes provided with heat absorbing fins which have the form of metal plates 37 mounted at intervals 105 on the respective parts of these tubes and provided with collars 38 around the openings which receive these tubes and are soldered thereto, also corrugations 39 which increase the absorbing area of the fins, and also beads or ribs 40 in the angles or corners of these corrugations for stiffening the same.

The transfer pipes serve to stiffen the vaporizer as a whole due to the connection between the two headers or manifolds, but if desired additional connections may be provided between the several parts of the vaporizer in order to prevent distortion of the same while being handled or installed, such for instance as the brace plate 43 connecting the opposing ends of some of the absorbing fins, as shown in Figs. 1, 3 and 4.

The lower ends of the fins of the lower absorber unit form rests for supporting the tubes on any suitable surface within the re-

frigerator compartment to be cooled but in addition it is preferable to employ a sheet metal leg 41 which is secured to the foremost upturned front parts of the lower tube 5 cluster so as to form a more effective support for the vaporizing chamber on the available surface for this purpose.

The form of vaporizer shown in Figs. 1-5 is exposed to the atmosphere for directly 10 cooling the air in the compartment which receives the vaporizer on the dry system, but when this vaporizer is to be used in a refrigerator working on the wet system then the vaporizing chamber, tubes, and associated 15 parts are placed within a container 42, as shown in Figs. 6 and 7, which container is filled with brine through the medium of which the heat in the compartment to be cooled is indirectly absorbed in a well known 20 manner. When a brine container is employed then the front end of the same is closed by a flange 44 on the front head of the vaporizing chamber which is connected by screws 45 or otherwise with said container, as shown in Figs. 6 and 7.

In this last mentioned construction the vaporizing tank or chamber is supported on the bottom of the container by a foot or leg 42.

30 For the purpose of preventing violent ebullition of the liquid as the same issues from the upper ends of the pipe 30 into the tank 10 a baffle 46 is arranged over the outlet ends of these pipes within the tank and 35 secured to the adjacent bottom part thereof, as shown in Figs. 1 and 10. This baffle intercepts the boiling liquid and directs the same horizontally rearward in the tank so as to quiet the same and give off its gas 40 without producing excessive foaming and thus ensuring a drier gas delivery from the tank and less back frosting.

It will be noted that the upper part of the manifold 20 and the pipes 17 connecting 45 the same with the tank 10 are above the liquid level in the latter, thereby ensuring prompt transference of gases from the top of the manifold 20 to the tank and increasing the cooling efficiency of the unit according 50ingly.

In both forms of this vaporizer considerable less solder and metal are required for the same cooling capacity of the refrigerator, clogging of the exterior of the same is 55 reduced to a minimum, and a substantial reduction in the amount of refrigerant for operating the vaporizer is effected.

I claim as my invention:

60 1. A vaporizer for refrigerator systems, comprising a plurality of parallel tubes adapted to receive the refrigerant, and a plurality of heat absorbing fins arranged on said tubes and spaced apart from one another each of said fins being corrugated and said 65 corrugations being stiffened by beads or ribs

formed on the fins at the corners or angles of said corrugations.

2. A vaporizer for refrigerator systems, comprising a vaporizing chamber, and a plurality of sets or clusters of vaporizing tubes, one set being straight and connected at one end with an end of said chamber, and the other set being of elbow form and having parts thereof parallel with the first mentioned set and other parts at right angles thereto and connected with the side of said chamber, a manifold connecting the rear ends of the tubes of each set, and pipes connecting said manifolds. 70

3. A vaporizer for refrigerator systems, comprising a vaporizing chamber, and a plurality of sets or clusters of vaporizing tubes, one set being straight and connected at one end with an end of said chamber, and the other set being of elbow form and having parts thereof parallel with the first mentioned set and other parts at right angles thereto and connected with the side of said chamber, a manifold connecting the rear ends of the tubes of each set, pipes connecting said manifolds, absorber fins arranged on the tubes of said sets, and braces connecting adjacent fins of said sets. 80 85

4. A vaporizer for refrigerator systems, comprising a vaporizing chamber, and a plurality of sets or clusters of vaporizing tubes, one set being straight and connected at one end with an end of said chamber, and the other set being of elbow form and having parts thereof parallel with the first mentioned set and other parts at right angles thereto and connected with the side of said chamber, a manifold connecting the rear ends of the tubes of each set, transfer pipes connecting said manifolds, absorber fins arranged on the tubes of said sets, braces connecting adjacent fins of said sets, and a leg secured to transverse parts of some of said elbow shaped tubes and adapted to support said vaporizing chamber. 90 95 100 105 110

In testimony whereof I hereby affix my signature.

FRANKLIN G. SLAGEL
